Inventor
Louis E. Mack.

by Watson E. Coleman
Attorney

UNITED STATES PATENT OFFICE.

LOUIS E. MACK, OF PHILADELPHIA, PENNSYLVANIA.

BROOM.

Application filed June 23, 1923. Serial No. 647,329.

To all whom it may concern:

Be it known that I, LOUIS E. MACK, a citizen of the United States, residing at Philadelphia, in the county of Philadelphia and State of Pennsylvania, have invented certain new and useful Improvements in Brooms, of which the following is a specification, reference being had to the accompanying drawings.

10 This invention relates to brooms, and one of the objects of the invention is to provide means attached to the lower end of the handle of the broom for holding the broom fiber in place against displacement and for 15 more firmly connecting or engaging the broom fiber with the handle of the broom.

A further object is to provide a construction of this character wherein the broom handle is provided with a fiber holder and 20 wherein the broom fiber, the handle and the holder are connected by an initially plastic or semi-liquid binder which fills the interstices between the broom fibers and around the holder and handle so as to bind the 25 broom fibers to the holder and to the handle.

A still further object is to provide a broom construction of this character wherein the agglutinated fibers with the holder and handle are enclosed within an outer casing.

30 My invention is illustrated in the accompanying drawings, wherein:—

Figure 1 is a side elevation of a broom constructed in accordance with my invention;

Figure 2 is a section on the line 2—2 of 35 Figure 1;

Figure 3 is a side elevation of the lower portion of the handle with the holder thereon;

Figure 4 is a section on the line 4—4 of 40 Figure 3.

Referring to the drawings, 10 designates the handle of the broom, which is of any ordinary or suitable form, and disposed adjacent the lower end of this handle is a 45 broom fiber or broom straw holder consisting of a metal strip formed at its middle to provide a split ring 11 adapted to embrace the lower end of the broom stick and be nailed or otherwise attached thereto, this 50 strip having the arms 12 and the transversely extending projections 13 projecting out on each side of the arms. Thus these projections form recesses 14.

The fibers of the broom or broom straws,

designated 15, are disposed in these recesses 55 14 and between and against the projections 13 so as to fill the spaces defined by said projections, as most clearly shown in Figure 2. A wire or string 16 is passed around the mass of fibers or straws at a suitable distance below the lower end of the broom stick and then the top portion of the fibers or 60 broom straws surrounding the broom stick and the head is given an asphalt solution which fills the spaces between the interstices 65 of the fiber or broom straw and binds the broom straws or fibers to each other and to the head or holder and to the lower end of the broom stick so that the upper end of the broom is formed of an agglutinated mass 70 within which the head or holder is firmly embedded. After this has been done a cover 17, preferably of leather but which may be made of any suitable material, is disposed around the upper end of the broom or 75 around that portion which has been filled with asphalt, this cover or casing 17 being held in place by a transversely extending rivet 18.

Above the upper end of the agglutinated 80 fibers, straws, etc., is disposed a somewhat conical cover 19 which is preferably made of leather but may be of any other suitable material, which entirely encloses the top of the broom and which is tacked to the handle of 85 the broom. This leather covering extends down over the cover or casing 17 and may be riveted or otherwise attached thereto, as illustrated in Figure 2.

It will be understood, of course, that the 90 broom has an elliptical form in cross section and that the casing 17 has, therefore, an elliptical form in cross section, as has the cover 19.

A broom constructed in accordance with 95 this invention is very solidly connected to the handle and the holder keeps the broom in shape, holds the broom straws or fibers rigidly in place, and the asphalt solution tends to prevent the individual broom straws 100 or fibers from pulling out of place. The casing 17 is, of course, tightly bound around the upper ends of the agglutinated material and the cover finishes the broom.

I do not wish to be limited to the exact 105 shape of the holder or head formed by the parts 11, 12 and 13, as this may be varied in many ways without departing from the

spirit of the invention. Neither do I wish to be limited to the use of an asphalt solution applied to the interstices between the fibers of the broom, as any other binder may 5 be used.

I claim:—

1. In a broom, a stick, an anchoring member secured upon the end of the stick and including oppositely extending elongated 10 members each carrying a plurality of spaced cross members defining a series of recesses, a bundle of broom material engaged about said anchoring member and within the recesses thereof, a binder clamped about the 15 bundle of broom material, and a cap engaged upon the outside of the binder and embracingly engaging the stick.

2. In a broom, a stick, an anchoring member secured upon the end of the stick and including oppositely extending elongated 20 members each carrying a plurality of unequally spaced cross members defining a series of recesses, a bundle of broom material engaged about said anchoring member and 25 within the recesses thereof, a binder clamped about the bundle of broom material, a cap engaged upon the outside of the binder and embracingly engaging the stick, and cemen-

titious material coating the butt end of the bundle of broom material.

3. In a broom, a stick, an anchoring member mounted upon the stick at one end thereof and including a split ring having oppositely elongated members extending therefrom, the anchoring member further including transverse elements projecting from the elongated members, a bundle of broom material engaged about the anchoring member and within the recesses defined by the transverse elements, a clamping member engaged about the bundle of broom material, a securing element fastened through the clamping member and through the bundle beyond the end of the stick and a cap engaged upon the clamping member and engaging the 45 stick.

4. In a broom, an anchoring member formed as a split ring having oppositely arranged elongated elements and a plurality of transverse elements projecting from both 50 sides of the longitudinal elements and arranged in spaced relation.

In testimony whereof I hereunto affix my signature.

LOUIS E. MACK.
